UNITED STATES PATENT OFFICE

WILLIAM J. MOORE, OF WASHINGTON, DISTRICT OF COLUMBIA, ASSIGNOR OF ONE-HALF
TO JOHN JANNEY, OF LEESBURG, VIRGINIA

DESIGN FOR A HANDLE FOR AUTOMOBILE DOORS AND THE LIKE

Application filed May 17, 1932. Serial No. 43,833. Term of patent 7 years.

To all whom it may concern:

Be it known that I, WILLIAM J. MOORE, a resident of Washington, D. C., and a citizen of the United States, have invented a new, original, and ornamental Design for Handles for Automobile Doors and the like, of which the following is a specification, reference being had to the accompanying drawing, forming a part thereof.

In the drawing:

Fig. 1 is a perspective view of an automobile door handle embodying my invention;

Fig. 2 is a side elevation thereof;

Fig. 3 is a cross-section on the line 3-3 of Fig. 2;

Fig. 4 is a cross-section on the line 4-4 of Fig. 2.

The handle embodying my design is a graceful compound curve in side elevation

with opposite curvatures proceeding from a boss or hub of circular form, the portions on opposite sides of the hub being of unequal length and in the proportion shown in the drawing and with the corners gently rounded convexly and top and bottom surfaces being substantially flat between the rounded corners on opposite sides. The longer arm curves generally upward from the hub and the shorter arm curves generally downward from the hub.

I claim:

The ornamental design for a handle for automobile doors and the like as shown and described.

In testimony whereof I hereunto affix my signature.

WILLIAM J. MOORE.
